UNITED STATES PATENT OFFICE.

GEORGE T. ROBINSON, OF BUFFALO, NEW YORK.

DESIGN FOR A TROUSERS-HANGER.

SPECIFICATION forming part of Design No. 37,469, dated June 20, 1905.

Application filed December 5, 1904. Serial No. 235,638. Term of patent 7 years.

To all whom it may concern:

Be it known that I, GEORGE T. ROBINSON, a citizen of the United States, residing at Buffalo, in the county of Erie and State of New York, have invented a new, original, and ornamental Design for a Trouser-Hanger, of which the following is a specification, reference being had to the accompanying drawing, forming a part thereof.

10 The figure is a perspective view of a trouser-hanger, showing my new design.

What I claim as new, and desire to secure by Letters Patent, is—

The ornamental design for a trousers-hanger as shown.

GEORGE T. ROBINSON.
